J. J. RADEL

GOLF CLUB

Filed Feb. 21, 1927

INVENTOR
John J. Radel,
BY
George D. Richards,
ATTORNEY

UNITED STATES PATENT OFFICE.

JOHN J. RADEL, OF NEWARK, NEW JERSEY.

GOLF CLUB.

Application filed February 21, 1927. Serial No. 169,739.

This invention relates to improvements in golf-clubs; and the invention has reference more particularly to a novel construction of golf-club by means of which the golf ball 5 may be addressed from either left or right, as circumstances may make desirable, and especially by means of which the golf-ball may be more advantageously addressed when occupying bad or obstructed "lies." 10 The invention has for its principal object to provide a novel construction of golf-club, which may be made of any suitable material, either metal, wood or the like, and which is so constructed as to provide oppositely directed operative striking faces of desired pitch, inclination or other contour, so that the same may be employed in either left or right hand swings, and in other ways best adapted to the address of a ball in play 15 20 which may occupy unusual positions or awkward "lies."

Other objects of this invention, not at this time more particularly enumerated, will be clearly understood from the following 25 detailed description of the same.

The invention is clearly illustrated in the accompanying drawings, in which:—

Figure 1 is a front elevation of one form 30 of golf-club made according to and embodying the principles of the present invention; and Figure 2 is a side view of the same, with the handle shaft broken away.

Figure 3 is a perspective view of a modified form of my novel golf-club, embodying, 35 however, the general principles of my instant invention, the handle shaft also being broken away in this view.

Similar characters of reference are employed in all of the hereinabove described 40 views, to indicate corresponding parts.

Referring now to said drawings, the reference character 5 indicates the socketed shank of the golf-club head, from the lower extremity of which projects outwardly the 45 club-head or body. In my instant invention the club-head or body is on the general order of a midiron or a niblick, but consists in a main body 6 provided with an upper or top apex portion 7 from which extends oppositely presented diverging faces 8 and 9, of any desired angle of inclination or pitch

relative to the perpendicular. The respective faces 8 and 9 may be constructed to provide either slightly concave surfaces, as shown in Figure 1, or flat plane surfaces 55 as shown in Figure 3. The main body 6 of the club-head may be solid intermediate the respective face portions 8 and 9, as shown in Figure 1, especially if it is desired to provide a club of maximum weight; or the main body 60 6 may be cut away at its under side intermediate the face portions 8 and 9, as indicated at 10 in Figure 3, especially if it is desired to provide a club of minimum weight.

Attached to the socketed shank 5 of the 65 golf-club head, in any usual or suitable manner, is the customary handle-shaft 11, provided at its upper free end with the hand-grip portion 12, all as indicated in Figure 1.

It will be apparent that the player in making use of the novel club made according to the instant invention, may, by addressing the ball with a swing of the club from the player's right, utilize the face 8 on the player's left. It may often happen, however, 70 that the "lie" of the ball is such that to address the latter by a swing of the club from the player's right is awkward, or inconvenient, by reason of obstructions presented by the contour of the ground to club movements 75 in such direction, while, on the other hand, an approach to or address of the ball from the player's left, by swinging the club from left to right, is much easier or more convenient. In the latter case operation of the 80 club in the latter manner is easily permissible, and the face 9 on the player's right may then be utilized to such end. There are also other "lies" of the ball possible 85 whereby ease of address may be attained by 90 the selective use of either the one striking face or the other of the instant club. If the club-head faces are made slightly concave, as shown in Figure 1, niblick or lofting shots from either the left or right may be 95 most conveniently performed with the novel construction of club embodying my instant invention.

It will be understood that modifications 100 of the shape or contours of the novel club-head within the scope of this invention, and other than those already above mentioned

may be made without departing from the scope of said invention as defined in the appended claim.

Having thus described my present invention, I claim:—

A golf-club comprising an open inverted V-shaped member providing oppositely presented flat inclined striking faces symmetrical to the vertical axis of said member and of

equal angular pitch, and a socketed handle 10 shank receiving portion integrally connected with and extending upwardly from one end of said member.

In testimony, that I claim the invention set forth above I have hereunto set my hand 15 this 10th day of February, 1927.

JOHN J. RADEL.
